UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,340,505.

Specification of Letters Patent. Patented May 18, 1920.

Application filed June 30, 1917. Serial No. 177,913.

To all whom it may concern:

Be it known that I, WILLIAM A. SMITH, a citizen of the United States, residing at Denver, in the county of Denver and State 5 of Colorado, have invented certain new and useful Improvements in Rock-Drills, of which the following is a specification.

The present invention relates to rock drilling apparatus, and the primary object is to 10 provide novel, simple, and effective means for effecting the rotation of the drill bit, while being operated on by the drilling motor.

One embodiment of this invention is illustrated in the accompanying drawings, 15 wherein:—

Figure 1 is a view in elevation of the apparatus,

Fig. 2 is a longitudinal sectional view on 20 an enlarged scale through the main portion of the same,

Fig. 3 is a cross sectional view on the line 3—3 of Fig. 2,

Fig. 4 is a detail sectional view substantially on the line 4—4 of Fig. 3,

Fig. 5 is a detail sectional view taken substantially on the line 5—5 of Fig. 2.

Similar reference numerals designate corresponding parts in the figures of the drawings.

In the embodiment illustrated, a drilling motor, designated generally by the reference numeral 6, is employed, projecting forwardly from a head block 7, which head block carries rearwardly extending extensible feeding means 8. Considering first the head block 3, it will be seen that it comprises a body portion formed of sections 9 and 10 having an interfitting joint 11. The extensible feeding means consists of the usual cylinder member 12 having a piston 13 therein, the cylinder member in this instance being coupled to the head block by being abutted thereagainst and surrounded by a collar 14 through which pass tie bolts 15 that are engaged with the front section 10 of the head block, as shown at 16, in Fig. 1. These tie bolts thus serve to clamp the cylinder member to the rear section 9 of the head block, and also clamp the two sections 9 and 10 together. Formed in the head block and extending through the section 10 and into the section 9, is a forwardly extending socket 17. It will be noted that the rear end of the cylinder member 6 has a rearwardly extend-

ing flange 6^a forming an annular groove for receiving the front end of the head block section 10. This produces a joint that prevents the dirt and muck from entering the parts within the same.

The drill actuating motor 6 may be of any desired type, though preferably of the valveless character. It consists of a cylinder member 18 having a piston chamber 19, in which operates the head 20 of a hammer 65 piston. This hammer piston is provided with a rearwardly extending neck 21 having a reduced portion 22 disposed adjacent to the head 20. The neck portion operates in a reduced chamber 23 communicating with the 70 chamber 19 and extending rearwardly therefrom. When the motor is in operation, motive fluid, preferably air, is constantly supplied into the rear portion of the chamber 23 as is hereinafter explained, and the supply of this motive fluid passes through channels 24 and 25 alternately to opposite sides of the head 20, this supply being controlled by the neck 21 with its reduced portion 22 in a manner well understood to those skilled 75 in the art. The exhaust from the motor takes place through the passageway 26.

The hammer piston 20 in this instance instead of operating directly upon the drill bit, has its blow transmitted to the said drill 80 bit through a tappet 27 mounted in a chuck 28 fixed to the front end of the cylinder and constituting a head therefor. The chuck 28 is provided with a sleeve 29, in which is non-rotatably but detachably and slidably located the drill bit, a portion of which is 85 shown at 30.

The rear end of the cylinder member 18 has a reduced gudgeon extension 31 that is rotatably located in the socket 17 of the 90 head block, and on this gudgeon portion and really forming a part thereof, is detachably fitted a sleeve 32 having an integral worm wheel 34 that is rotatable in a chamber portion 35 formed in the head block. It will be 95 seen that this wheel is in the nature of a flange that is located between the two sections 9 and 10 of the head block, so that its movement in either direction longitudinally of the machine is prevented, and a washer 100 36 is preferably located against the rear side of this worm wheel, the joint being furthermore provided with a packing gasket 37. The detachable sleeve has its rear portion keyed, as shown at 38, to the extension 31 110

of the cylinder member, and is held to said extension by washers 39 abutted thereagainst and held in place by a screw plug 40 threaded into the rear end of said extension 5 37. The parts are thus all effectively held together.

Motive fluid supplied from any suitable source is conducted by suitable means to a nipple 41 formed upon the head block and 10 communicating with a valve casing, in which is located the usual rotatable throttle valve 42. The bore 43 of this valve is in constant communication with the motive fluid supply, and is provided with lateral ports 44, 45 and 15 46. The port 44 is movable into and out of communication with a passageway 47 that communicates through a series of ports 48 with the neck chamber 23, and the ports 45 and 46 are movable into and out of communication with a passageway 49 that 20 conducts motive fluid to the extensible feeding means 8. It will be evident that when all the ports 44, 45 and 46 are out of communication with the passageways 47 and 49, motive 25 fluid is cut off from the machine. If the port 45 is brought into communication with the passageway 49, motive fluid flows to the feeding means in sufficient quantity to cause the extension thereof, and thus raise 30 the drill actuating motor to its work. If the valve is turned until the ports 44 and 46 are brought respectively into communication with the passageways 47 and 49, motive fluid is supplied both to the feeding means 35 and to the drill actuating motor, so that the latter is operated, and as the drill hole is deepened, the motor is kept up to the work.

For the purpose of rotating the drilling motor with respect to the feeding means and 40 head block and thus rotating the drill bit, the following mechanism is preferably employed. A rotary motor is located upon one side of the head block, and consists of a casing 50 having a detachable head 51 and containing 45 a pair of intermeshing geared pistons 52 and 53. The piston 52 is an idler, being provided with a roller bearing 53^a operating on a shaft 54 that extends across the casing and has a bore 55 therethrough. 50 The other piston 53 is keyed to a shaft 56 that projects into the head block, and has a worm 57 in mesh with the worm wheel 34, which as already described, is keyed to the drilling motor. The shaft 56 is provided 55 with suitable bearings 58 and 59. The head 51 of the rotary motor casing 50 has an extension constituting a handle grip 60 provided with a chamber 61 in communication with the bore 55 of the shaft 54, and leading 60 to said bore 55 is a passageway 62 that is in communication with the motive fluid supply, as indicated in dotted lines in Fig. 1. Leading from the chamber 61 is a passageway 63 that opens into the rotary motor at 65 one side of the intermeshing portions of the

pistons. An exhaust passageway 64 leads from the opposite side to the outer atmosphere. The chamber 61 at its point of communication with the bore 55 of the shaft 54, has a valve seat 65, and movable into and 70 cut off coöperation with the valve seat, is a plug valve 66 carried by a screw handle 67 that is threaded on a stem 68. This stem is screwed into the outer end of the chamber and constitutes a closure therefor. It will 75 be evident that by rotating the handle 67 upon the stem 68, the valve may be seated or unseated, as desired.

The operation may be briefly outlined as follows: When motive fluid is introduced 80 into the drill actuating motor and to the feeding means as above explained, the said motor will be held to its work, and will be in operation. The rotation of the drill bit is effected by the bodily rotation of the drilling motor, and the rotation of said drilling motor, it will be observed, is independent of the rotation of the feeding means. That is to say, the feeding means and head block are held against rotation by the handle, comprising the parts 60 and 67. To effect the rotation of the drilling motor, it is only necessary for the operator grasping the handle 60—67, to turn the part 67 in the proper direction and unseat the valve 66, whereupon the motive fluid will pass through the passageway 62, bore 55, chamber 61 and passageway 63 into the rotary motor, effecting the rotation of the pistons thereof. The rotation of this piston will, of course 95 turn the shaft 56, the worm 57 and the worm wheel 34. Inasmuch as this worm wheel is keyed, as shown at 38 to the drilling motor, the latter will be rotated, and consequently the drill bit will be turned with it. 100

Means are also provided for supplying a cleansing fluid to the drill bit. It will be noted by reference to Fig. 2 that said drill bit 30 has as usual a bore 70 longitudinally therethrough for the purpose of conducting 110 cleansing fluid to the bottom of the drill hole to eject the cuttings. The rear section 9 of the head block is provided with a socket 71 in which is fitted the rear end of a tube 72 that passes through the plug 40, 115 through the piston 20—21, through the tap-pet 27, and into the bore 70. This rear end is held in place by a plug 73. A nipple 74, located at one side of the head block, provides means for coupling a water supply 120 hose and from this nipple a passageway 75 leads to and is in communication with the rear end of the tube 72. Water or other cleansing fluid can thus be passed through the motor to the drill bit. It will be noted 125 that this tube 72 is held against rotation, and that the drilling motor is rotatable about the same as an axis.

From the foregoing, it is thought that the construction, operation and many ad- 130

vantages of the herein described invention will be apparent to those skilled in the art, without further description, and it will be understood that various changes in the size, 5 shape, proportion, and minor details of construction, may be resorted to without departing from the spirit or scope of the invention.

Having thus fully described my invention, 10 what I claim as new, and desire to secure by Letters Patent, is:—

1. In apparatus of the character set forth, the combination with a head block having a socket, a valve casing in the head block at 15 one side of the socket, and a gear casing at the opposite side of the socket, of a drilling motor having a portion journaled in the socket, extensible feeding means connected to the rear end of the head block, channels 20 for conducting motive fluid from the valve casing to the feeding means and to the motor, a throttle valve journaled in the casing for controlling the supply of motive fluid and having a handle at one side of the 25 head block, a rotary motor mounted on the casing at the opposite side of the head block and including gear mechanism in the gear casing, and a handle projecting from the rotary motor.

30 2. In apparatus of the character set forth, the combination with a head block comprising separable sections and having a bearing socket, of a motor having a gudgeon portion rotatable in the socket, and a retaining member 35 detachably mounted on and surrounding the gudgeon portion and interposed between the sections of the head block to prevent the disengagement of the gudgeon portion from the socket, and means for 40 normally securing the retaining member on the gudgeon.

3. In apparatus of the character set forth, the combination with a head block having a bearing socket and divided transversely 45 thereof into separable sections, of a motor having a gudgeon portion rotatably mounted in the socket, and a sleeve detachably mounted on the gudgeon portion and operating between the head block sections to retain the gudgeon portion in the socket.

50 4. In apparatus of the character set forth, the combination with a head block having a bearing socket and divided transversely thereof into separable sections, of a motor having a gudgeon portion rotatably mounted in the socket, a gear element detachably mounted on the gudgeon portion and operating between the head block sections to retain the gudgeon portion in the 55 socket, means for holding the gear element on the sleeve and preventing their relative rotation, and means engaged with the gear element for effecting the rotation of the motor.

65 5. In apparatus of the character set forth,

the combination with a head block having a bearing socket and divided transversely thereof into separable sections, of a motor having a gudgeon portion rotatably mounted in the socket, a sleeve detachably keyed 70 to the gudgeon portion and having a gear element interposed between the sections of the head block, means on the rear end of the gudgeon portion for securing the sleeve, and means mounted in the head block and 75 engaged with the gear element for effecting the rotation of the motor.

6. In apparatus of the character set forth, the combination with a head block comprising sections, of a motor rotatably mounted 80 in the head block and having a portion interfitted in the sections to hold the motor and head block against separation, extensible feeding means for the motor, and common means for securing the feeding means 85 to the head block and the sections of the head block together.

7. In apparatus of the character set forth, the combination with a head block comprising front and rear sections, of a motor rotatably mounted in the head block, extensible feeding means for the motor, and side bolts 90 connecting the feeding means and front section to clamp the sections together and secure the feeding means to the head block. 95

8. In apparatus of the character set forth, the combination with a head block comprising front and rear sections and having a socket, of a motor having a gudgeon portion journaled in the socket, a retaining element 100 detachably mounted in the gudgeon portion and located between the sections, extensible feeding means for the motor, and side bolts connecting the feeding means and front section of the head block. 105

9. In apparatus of the character set forth, the combination with a head block having a socket and a valve casing in the head block at one side of the socket, of a drilling motor having a portion journaled in the socket, a 110 motor for rotating the drilling motor, fluid supply passageways from the valve casing to the drilling motor and rotating motor, a throttle valve in the casing controlling the fluid supply to the drilling motor, a handle 115 for holding the head block, and a valve operated by the handle for controlling the fluid supply to the rotating motor.

10. In apparatus of the character set forth, the combination with a head block 120 having a socket, a valve casing in the head block at one side of the socket, and a supply nipple communicating with the casing, of a drilling motor having a portion journaled in the socket, a motor mounted on the head block for rotating the drilling motor, a fluid supply passageway from the valve casing to the drilling motor, a throttle valve in the casing controlling said fluid supply passage- 125 way, a handle for holding the head block, 130

a fluid supply passageway from the nipple through the handle to the rotating motor, and a valve operated by the handle for controlling the latter passageway.

5 11. The combination with a head block having a socket, of a drilling motor having a gudgeon portion in the socket and including a removable sleeve having a gear thereon and constituting means for retaining the 10 gudgeon portion in the socket, and a drill rotating motor mounted on the head block and having gear connections with said gear.

12. The combination with a head block having rearwardly projecting motive fluid 15 operated feeding means and a forwardly extending socket, of a drilling motor having a drill receiving chuck and also having a rearwardly extending gudgeon portion rotatably mounted in the socket, a sleeve mounted on 20 said gudgeon portion and also located in the socket, said sleeve having a worm gear, a rotary motor located upon one side of the head block and including a transverse shaft having a worm engaged with the worm 25 gear, and means on said head block for controlling the supply of motive fluid to the drilling motor, to the rotary motor and to the feeding means.

13. The combination with a drilling motor comprising a cylinder member and a piston operating therein, of means passing

through the piston for delivering cleansing fluid to a drill bit operated on by said piston, said drilling motor and means being relatively rotatable, and means for effecting 35 their relative rotation.

14. The combination with a drilling motor, of a head block connected therewith, a water tube fixed to the head block and extending through the motor, means for rotatably connecting the motor with the head block, and means for rotating the motor with respect to the head block and tube. 40

15. The combination with a support, of a drill actuating motor rotatably mounted on 45 the support, a rotary motor geared to the drill actuating motor for rotating the same and including a rotary piston, a journal bearing for the piston comprising a hollow shaft, means for supplying motive fluid to 50 said shaft, means for delivering the motive fluid passing through said shaft to the rotary motor, including a hollow handle stem, and a valve mounted on said stem and controlling the fluid supply. 55

In testimony whereof, I affix my signature in the presence of two witnesses.

WILLIAM A. SMITH.
